UNITED STATES PATENT OFFICE.

JOHN J. HENNESSEY, OF MILWAUKEE, WISCONSIN.

FRICITION DRAFT-RIGGING FOR RAILWAY-CARS.

SPECIFICATION forming part of Letters Patent No. 717,676, dated January 6, 1903.

Application filed November 5, 1902. Serial No. 130,135. (No model.)

To all whom it may concern:

Be it known that I, JOHN J. HENNESSEY, a citizen of the United States, residing in Milwaukee, in the county of Milwaukee and State 5 of Wisconsin, have invented a new and useful Improvement in Friction Draft-Rigging for Railway-Cars, of which the following is a specification.

My invention relates to friction draft-rigging for railway-cars.

The object of my invention is to provide a friction draft-rigging of a simple, strong, efficient, and durable construction in which the opposing or engaging friction-faces are composed of suitable metals of different kinds 15 or characters to produce proper wearing and friction effects—such, for example, as malleable iron against cast iron or steel—without interfering with the strength of the draft-rigging or of the different parts thereof and without adding to the cost of manufacture.

My invention consists in the novel construction of parts and devices and in the novel combinations of parts and devices herein 25 shown and described by which this object or result is accomplished.

In the accompanying drawings, forming a part of this specification, and in which similar letters of reference indicate like parts in all 30 the figures, Figure 1 is a central vertical section of a friction draft-rigging embodying my invention, taken on the line 1 1 of Fig. 2. Fig. 2 is a plan view; Fig. 3, a vertical cross-section, on line 3 3 of Fig. 1. Fig. 4 is a perspective view of the draft-iron. Fig. 5 is a cross-section on line 5 5 of Fig. 4. Fig. 6 is a longitudinal section on line 6 6 of Fig. 3. Fig. 7 is a detail plan, partly in horizontal 35 section, of the friction-block. Fig. 8 is a detail perspective of the friction-face insert for the friction-block; and Figs. 9 and 10 are views similar to Figs. 7 and 8, respectively, showing a modified form of the friction-face insert.

45 In the drawings, A represents the draft-timbers, A' the center sills, A² the cross-sill, A³ the buffer-block, A⁴ the buffer-plate, A⁵ the carry-iron, B the draw-bar, and B' the coupler, these parts being all of any suitable construc-

50 D is the sliding friction-draw-bar extension or draft-iron, the same being directly in

line with the draw-bar and connected thereto by a clip or yoke b, passing through an eye d in the draw-bar extension or draft-iron. 55 The draft-iron D is preferably made of malleable iron, and it has on one side, preferably its upper side, a straight friction-face d², and on its opposite side, preferably its lower side, double-incline friction-faces d³ d⁴, the same 60 being formed on inserts d⁸ of different frictional or wearing material from the draft-iron itself, and preferably cast-iron in cases where the draft-iron is of malleable iron. The inserts d⁸ fit on each side of the central web d⁵ 65 of the draft-iron and under the horizontal web d⁹ thereof and are each furnished with notches, recesses, or shoulders d¹⁰ to fit the corresponding projections d¹¹ on the draft-iron. The inserts d⁸ are secured in place by 70 bolts d¹², passing through the vertical web d⁵ of the draft-iron.

F F are the side plates or stop-castings of the draft-rigging, the same fitting between the draft-timbers and securely attached thereto by bolts f. The stop-castings F are preferably of malleable iron, and each is provided at its central upper portion with a recess or socket f' to receive the ends g of the stationary friction-plate G, so as to securely hold and 75 anchor the same in position above the longitudinally-movable draft-iron D and in sliding frictional engagement with the straight friction upper face d² thereof and in the central line of draft. Each of the stop-castings F is 80 also furnished with transverse or upright guides or flanges f² to guide and hold longitudinally in position the transversely-movable friction-block H. The guides or flanges f² are extended at their lower ends to form 85 downwardly-projecting lugs f³ to receive, support, and anchor in position the removable spring seat or barrel K, against which the lower end of the transversely-acting spring K' bears. Both of the stop-castings F are 90 provided, or preferably provided on their inner faces with horizontal strengthening ribs or flanges f⁴ and vertical ribs or flanges f⁵, the latter forming guide-faces for the transversely-movable friction-block H. Each of 95 the side plates or stop-castings F is also provided with a horizontally-projecting wing f⁶, having interlocking or interengaging notches or tongues f⁷ and f⁸, and which abutting or

interlocking wings are secured together by bolts f^9 , so as to give additional strength to the structure as a whole.

The vertically or transversely movable friction-block H has double-incline friction-faces $h\ h'$, which bear against the corresponding double-incline friction-faces $d^3\ d^4$ on the draft-iron when the draft-iron moves longitudinally under either pulling or buffing strains. In case, as illustrated in Figs. 1, 2, 3, and 4, double-incline friction-faces $d^3\ d^4$ on the draft-iron are formed in inserted blanks d^8 of different material from the draft-iron the corresponding friction-faces $h\ h'$ on the friction-block H may, if preferred, be made of the same material as the draft-iron—as, for example, malleable iron. In cases where, however, as illustrated in Fig. 6, the double-incline friction-faces $d^3\ d^4$ on the draft-iron are formed integrally with the draft-iron or of the same material as the draft-iron I form the double-incline friction-faces $h\ h'$ of the friction-block H in inserts or blocks h^4 of different material from the block H, so as to afford friction-wearing-surfaces of different material. The inserts or blocks h^4 are preferably of the shape illustrated in Figs. 7 and 8 and are secured in place by pins or rivets h^5 . In Figs. 9 and 10 the friction insert-blocks h^4 are shown 30 of a different shape.

The friction-block H is provided with a longitudinal groove h^2 to receive the longitudinal web d^5 of the draft-iron. The friction-block H is also provided with an integral 35 downwardly-projecting flange or cup h^3 to receive and guide the spring K'.

In the drawings I have illustrated my invention as applied to a friction draft-rigging having only a single friction-block H and 40 spring K'. It is, however, equally applicable for use upon friction draft-rigging having two

or more friction-blocks H, the draft-iron D having in such case more than one pair of incline friction-faces.

The spring seat or cup K is removably secured in place by cotter-bolts K^2 , having keys K^3 .

The draft-iron D has stop-shoulders $d^6\ d^7$, which engage corresponding shoulders $f^{10}\ f^{11}$ on the side plates or stop-castings to limit the 50 longitudinal movement of the draft-iron and draw-bar.

The stationary friction face or plate G is of a different material from the draft-iron, and preferably of cast iron or steel in cases where 55 the draft-iron is of malleable iron. The opposing interengaging friction-faces are thus by my invention all made of different material, so as to secure proper frictional and wearing qualities, and this applies not only 60 to the straight friction-faces d^2 and G, but also to the double-incline friction-faces $d^3\ d^4$ and $h\ h'$. Although the double-incline friction-faces which are formed on the inserted pieces or blocks may be on either of the two 65 parts, (draft-iron D and friction-block H,) I prefer to provide the draft-iron D with the inserted pieces or blocks.

I claim—

In a friction draft-rigging, a draft-iron having 70 a straight friction-face on one side and double-incline friction-faces on its opposite side, and a central web, said double-incline friction-faces being formed in inserted blocks or pieces of different material and secured in 75 place by fastenings extending through the central web of the draft-iron, substantially as specified.

JOHN J. HENNESSEY.
